HANGING CHAIR

Helen N. McGreevy and Joe E. Cotta, both of 77
Estabrook St., San Leandro, Calif. 94577

Filed Feb. 12, 1973, Ser. No. 331,668

Term of patent 14 years

U.S. Cl. D6—47   Int. Cl. D6—01

FIG. 1 is a perspective view of a hanging chair showing our new design;

FIG. 2 is a front elevational view on an enlarged scale;

FIG. 3 is a left side elevational view;

FIG. 4 is a rear elevational view; and

FIG. 5 is a bottom plan view on an enlarged scale.

We claim:

The ornamental design for a hanging chair, substantially as shown and described.
